FILTER CIRCUITS

Irwin B. Levine, Newark, N. J., assignor to Wired Radio, Inc., New York, N. Y., a corporation of Delaware

Application March 14, 1930, Serial No. 435,694

1 Claim. (Cl. 178—44)

My invention relates to electric wave transmission systems and pertains particularly to that class of selective wave transmission systems which are termed "band pass filters".

5 One of the objects contemplated by my invention comprises providing means for increasing the transfer of energy through band pass filters having terminal impedances of unequal magnitudes.

10 Another object of my invention is to produce a filter adapted to operate with maximum efficiency between unequal impedances.

Another object contemplated by my invention consists in producing a novel filter adapted to transfer energy with maximum efficiency between unequal impedances and yet constructed of few and simple parts to thus effect an appreciable reduction in the present cost of manufacture of such filters.

20 Other desirable features will be hereinafter pointed out and discussed.

Some type of wave filter is usually employed whenever it is desired to transmit an electric current of a given band of frequencies, to attenuate all frequencies above and below the range which it is desired to transmit. Many types of filters have been used for this purpose. One type consisting of positive and negative reactances, successive meshes of which are coupled together by electromagnetic inductance only, is described in "Heaviside's Electrical Circuit Theory" by a Dr. Louis Cohen. The use of such a wave filter in connecting impedances of like value is well known in the art.

35 To prevent reflection losses it is imperative that the output impedance of the sending organization connected in the filter, the characteristic impedance of the filter, and the input impedance of the receiving circuit to which the filter is connected, shall be equal. It, however, usually happens in practical applications that the sending and receiving circuits have characteristic impedances which are not equal but differ from each other by wide margins. For example, it 40 may be desired to transfer power through a filter from the anode circuit of a thermionic tube to conductors carried in a cable. In such a case, the input and output impedances will differ from each other very widely, and it has hitherto been difficult to produce a filter permitting transfer of maximum energy in such cases.

According to magnetic theory, there exists an ideal transformer having no leakage reactance and with infinite mutual reactance by means of

which a transformation of impedance is possible, such transformation being equal to the ratio of the primary impedance to the secondary impedance. Obviously, such a transformer could be used in the above example to efficiently connect the unequal impedances. In actual practice, the design of such a transformer is quite impossible and, in fact, cannot even be approximated at relative high frequencies.

To accomplish the transfer of maximum energy between unequal impedances, it has heretofore been the practice to utilize a filter network which increased greatly in complexity in the effort to obtain maximum transfer efficiency at a greater number of frequencies, thus increasing the cost of manufacture of such filters to an undesirable point.

It is the purpose of my invention to provide simple and effective means for accomplishing the maximum transfer of energy between unequal impedances at all frequencies which may be transmitted by a wave filter.

In the drawings accompanying and forming a part of this specification:

Fig. 1 shows diagrammatically a wave filter of the electromagnetic coupled type, the impedances of which are designed to transmit freely one band of frequencies between impedances of equal values.

Fig. 2 illustrates diagrammatically two filters, the characteristic impedances only of which differ from each other, connected by a transformer of ideal characteristics.

Figs. 3-5 diagrammatically illustrate the steps in the process of translating the filters shown in Fig. 2 and the hypothetical transformer between them into my novel equivalent practical network.

Figs. 6 and 7 show diagrammatically two practical applications of the transformation of impedance in accordance with my invention.

Referring now in particular to Figs. 1 and 2, Fig. 1 illustrates a type of electromagnetically coupled filter described in the publication of Dr. Louis Cohen hitherto mentioned herein, adapted to unite impedances of equal value and of a value equal to that of the characteristic impedance of the filter. It is the general type of electromagnetically coupled filter which I propose to improve and modify in carrying out my invention.

Referring to Fig. 2, filter A has identically the same characteristics as filter B, except that the characteristic impedances of the filters differ from each other by a ratio which will be herein-

after discussed. In the figure K designates the coupling coefficient between meshes,

$$\frac{L}{2},$$

the self-inductance of the coupling coil and C the capacitance of a whole mesh, the one half mesh capacitance being $2C$.

In filter A, the lower cut-off frequency is;

$$10 \quad f_1 = \frac{1}{2\pi \sqrt{LC\sqrt{1+K}}}$$

The upper cut-off frequency is;

$$15 \quad f_2 = \frac{1}{2\pi \sqrt{LC\sqrt{1-K}}}$$

The attenuation constant for any frequency which may be a frequency between the upper and lower cut-off frequencies is;

$$20 \quad A = \cosh^{-1}\left(\frac{\omega_0^2 - 1}{K}\right)$$

Where

$$25 \quad \omega_0 = \frac{1}{\sqrt{LC}} = \text{a constant,}$$

and $\omega = 2\pi f$, where f is any frequency for which the attenuation A is being computed. The characteristic impedance at any frequency Z_{s_A} for filter A is;

$$30 \quad Z_{s_A} = \frac{1}{2\omega C} \sqrt{-1 - \frac{\omega^2}{\omega_0^2} \left(\frac{\omega^2}{\omega_0^2} [1-K]^2 - 2 \right)}$$

35 In Filter B, the lower cut-off frequency is;

$$f_1 = \frac{1}{2\pi \sqrt{LC\sqrt{1+K}}}$$

40 The upper cut-off frequency is;

$$f_2 = \frac{1}{2\pi \sqrt{LC\sqrt{1-K}}}$$

The attenuation constant for any frequency which may be a frequency between the upper and lower cut-off frequencies is;

$$50 \quad A = \cosh^{-1}\left(\frac{\omega_0^2 - 1}{K}\right)$$

55 The characteristic impedance at any frequency Z_{s_B} for filters B is;

$$Z_{s_B} = \frac{a^2}{2\omega C} \sqrt{-1 - \frac{\omega^2}{\omega_0^2} \left(\frac{\omega^2}{\omega_0^2} [1-K]^2 - 2 \right)}$$

$$Z_{s_B} = Z_{s_A} a^2$$

The characteristic impedance of filter B is equal to the characteristic impedance of filter A multiplied by the factor a^2 . Since at every frequency the ratio of impedances of the filters is equal to a^2 an ideal transformer of ratio $1:a$ may be imagined between the two filters and then the impedances preceding and following the transformer changed in such manner as to realize practically all of the functions of the imaginary ideal transformer.

Referring now specifically to Figs. 3-5, I propose to illustrate graphically the transformation of the ideal organization shown diagrammatically in Fig. 2 into a practical equivalent. The first step is shown in Fig. 3 which shows a II network which is completely equivalent to the condensers $2C$ in series with an ideal transformer of ratio $1:a$.

Fig. 4 diagrammatically indicates a T network which is equivalent to the two coupling coils, each having a self-inductance of

$$\frac{L}{2}$$

80

and a coupling coefficient between the coils of K. These equivalences are well known in the art.

Fig. 5 shows diagrammatically a T network which is the exact equivalent of the T network of Fig. 4 in combination with the II network of Fig. 3 and the condenser

$$\frac{2C}{a^2}$$

93

of filter B, Fig. 2. Fig. 5 further illustrates by successive transformations of II networks into T networks, which transformations are all well known in the art, and each network successively operated on being indicated by a dotted circle, how the combination is finally resolved into a wave filter in all respects similar in type to that shown in Fig. 1, but in which at the point where a change of impedance by a factor as a^2 is desired all succeeding impedances are multiplied by the factor a^2 . The change in impedance is always effected at a point where two or more coils are coupled by electromagnetic induction. One or more coils may be associated with a wave filter mesh of characteristic impedance given by one equation, and one or more coils may be associated with a wave filter mesh of a characteristic impedance given by the same equation and multiplied by the factor a^2 .

By following the same procedure, it will be obvious that a transformation of characteristic impedance may be effected as many times as there are meshes coupled by electromagnetic induction to effect any desired transformation of impedance and to permit the output circuits of organizations being connected to the input circuit of other organizations having impedances of widely different values to permit of the transfer of energy from one organization to another through the filter with minimum reflection losses and hence with maximum efficiency.

In order to completely disclose my invention, I have shown in Figs. 6 and 7 two practical examples giving, therefore, the actual magnitudes of the component parts.

It was desired in the first example shown in Fig. 6 to provide a band pass filter to have a characteristic impedance of 50 ohms at its mean frequency and to transmit freely a band of frequencies from 44 kilocycles to 53 kilocycles. The filter is intended to work into a line whose impedance is 10 ohms at the mean frequency of 48 kilocycles and to transmit the maximum energy at the mean frequency. The complete practical design of the two preceding meshes and the final mesh with a transformed impedance is shown in Fig. 6.

The example shown in Fig. 7 illustrates the solution of the problem of providing a filter having an impedance of 50 ohms at its mean frequency and adapted to connect a transmitting amplifier into a line to transmit with maximum efficiency a band of frequency from 44 kilocycles to 53 kilocycles, the line impedance being of the value of 50 ohms. In this design, the condenser C has a value of .00615 microfarads in each mesh but one where it was found inconvenient to place such a condenser and a .005 microfarad condenser was substituted. The two inductances associated with the substituted condenser were 150

changed from .902 millihenrys to 1.108 millihenrys each as shown in the figure. In the mesh containing the .005 condenser, the characteristic impedance was at a point A—A stepped up by a factor of 1.229 and stepped down by the same factor at point B—B. No reflection loss or other change of filter characteristics were noted, thus illustrating one of the desirable features of my invention, that is, the increased latitude of selection in component parts, thus simplifying and cheapening manufacture.

It will be noted from the above that my improved filter provides a simple convenient means for transforming impedance to permit of the connection by a filter of unequal terminal impedances with minimum reflection losses, that such filter lends itself readily to cheap manufacture and that it admirably accomplishes the purpose of affording means for transferring energy be-

20

tween terminal impedances of unequal magnitude at maximum efficiency.

Having thus completely described my invention what I claim as new and desire to secure by United States Letters Patent is as follows:

A transmitting network adapted to connect a transmitting organization with a receiving organization in which transfer of energy is accomplished by meshes composed of positive and negative reactances connected by electromagnetic induction only, and in which the first half mesh and the last half mesh only are matched as to their characteristic impedances with the transmitting and receiving organizations, respectively, and in which the intermediate meshes have the same arbitrarily chosen impedance characteristics.
